UNITED STATES PATENT OFFICE.

ROBERT H. McLAIN, OF NEW YORK, N. Y., ASSIGNOR TO GENERAL ELECTRIC COMPANY, A CORPORATION OF NEW YORK.

ELECTRIC-RAILWAY SYSTEM.

Application filed November 21, 1924. Serial No. 751,228.

To all whom it may concern:

Be it known that I, ROBERT H. McLAIN, a citizen of the United States, residing at New York, in the county of New York, State of New York, have invented certain new and useful Improvements in Electric-Railway Systems, of which the following is a specification.

This invention relates to electric railway systems, particularly alternating current electric railway systems suitable for handling mail, parcels, freight and the like in which the cars or trains are without operators or motormen thereon and are controlled from points external to the cars or trains.

The invention has for its object, the provision of improvements in electric railway systems of the above character whereby the cars may be assembled into trains and dispatched from a plurality of loading tracks to a main track as well as disassembled and distributed therefrom to a plurality of receiving tracks in an efficient, safe and reliable manner.

Although of general application, the present invention is of particular utility where it is desired to transport freight or the like between stations having a plurality of loading and receiving tracks interconnected by a minimum number of main tracks which are normally energized from an alternating current source of relatively high frequency. When embodied in such a system, my invention enables a maximum number of trains to be accelerated and fed from the loading tracks to the main tracks as well as decelerated and distributed therefrom to the receiving tracks.

The invention may be carried into effect in a preferred form by dividing each of the several loading tracks into corresponding zones, a normally deenergized dispatching zone being located adjacent the junction of each loading track with the normally energized main track, and a normally deenergized waiting zone being located between the dispatching zone and the loading zone which is normally energized at a relatively low frequency. In accordance with the invention, the dispatching zones of the loading tracks are arranged to be separately energized from a source of variable frequency so as to accelerate and feed coupled trains of cars therefrom to the main track and the waiting zone of each of the loading

tracks is sectionalized and means are provided for successively energizing the sections of each waiting zone in order to couple the individual cars passing from the loading zone to the waiting zone into trains and move the coupled trains of cars to the dispatching zone.

Each of the cars is equipped with one or more alternating current driving motors and are provided with suitable current collecting devices as well as a controller for the driving motor arranged to permit manual control of the movement of the cars in the loading zone by an operator walking or standing beside the track.

After passing over the main track at high speed, the trains of cars may be switched to one of several receiving tracks each of which is energized at a lower frequency than the main track and is provided with a normally deenergized section adjacent the junction with the main track. In order to electrically decelerate the trains of cars, the normally deenergized sections of the receiving tracks are arranged to be separately connected to a source of variable frequency and means are provided whereby the frequency and voltage if desirable at which the driving motors of the cars are energized may be gradually decreased. The cars are then uncoupled and individually distributed to the proper unloading station.

The various novel features and combinations which I believe to be characteristic of my invention are pointed out with particularity in the appended claims and for a better understanding of the invention reference is had to the following description taken in connection with the accompanying drawings in which Fig. 1, diagrammatically illustrates the arrangement of the loading portion of the automatic electric railway system embodying my invention, Fig. 2, shows in diagrammatic form the operating mechanism with which each of the cars is equipped, Fig. 3, is a more detailed view of a preferred form of electro-magnetic brake for the cars, Fig. 4, diagrammatically illustrates the arrangement of the receiving portion of the automatic electric railway systems embodying my invention, and Fig. 5, is a detailed view partly in section of a preferred form of coupling arrangement for the cars.

Referring to Fig. 1, the loading portion of the automatic electric railway system com-

prises a plurality of loading tracks 10, 11, 12, 13 and 14 each of which joins with a main track 15 and is divided into a loading zone, a waiting zone, and a dispatching zone 5 as indicated in the drawing. A plurality of alternating current motor driven cars such as the cars C and C' are arranged to operate upon the tracks and power is supplied to operate the cars by means of suitable conductors located adjacent the various tracks such for example as the third rail illustrated although other forms of power conductors may be employed if desired. Furthermore it will be understood that altho only a single 15 power conductor is shown in the system illustrated and the tracks are employed as a return conductor, a number of power conductors may be located adjacent the tracks in case multiphase alternating current operation of the cars is desired.

As shown more in detail, in Fig. 2 each of the motor cars employed in the automatic railway system embodying the invention is arranged to be driven by a pair of alternating current electric motors 16 and 17, although it will be understood that one or more motors may be employed depending upon the size and weight of the individual cars. The driving motors 16 and 17 are suitably connected to be supplied with current through a circuit including one of the current collecting shoes 18 or 19 located at opposite corners of the car and the controller 20 which is manually operable to connect the motors for 30 operation in either direction. The controller 20 has the operating handles 21 and 22 at opposite ends thereof and is mounted upon the car so as to be operable conveniently from either side thereof.

40 In order to insure the automatic stopping of the cars upon the de-energization of the driving motor, an electromagnetic brake 23 is mounted upon the shaft of motor 16 and a similar electromagnetic brake 23' is 45 mounted upon the shaft of motor 17. Each of the brakes 23 and 23' preferably is of the type shown more in detail in Fig. 3 and which is fully described and claimed in my co-pending divisional application, Serial No. 50 30,974, filed May 18, 1925. Briefly, the electromagnetic brake comprises a rotatable member 24 adapted to be mounted upon the motor shaft and having a drum surface with 55 which the two opposing braking members 25 and 26 are biased to frictionally engage by suitable means such as the weight 27. An electromagnetic 28 is provided for operating the braking members 25 and 26 out of engagement with the rotatable member 24. In 60 accordance with the usual practice, the operating electromagnetic 28 is connected to be energized simultaneously with the energization of the motor with which the brake is associated. Since the conductors for supplying power to the motor driven railway

cars necessarily are interrupted at track switches, crossovers, and other similar portions of the track system, it is desirable to provide a retarding device to prevent the setting of the brakes during such momentary de-energization of the driving motors as will occur upon the passage of the car over such portions of the track. 70

As more fully set forth in my divisional application a dash pot 29 of the vacuum type is operatively connected to the movable brake members 25 and 26 to retard the operation thereof to the braking position. As shown in Fig. 3, the vacuum dash pot comprises a cylinder 30 and a piston 31 arranged to reciprocate therein. A check valve 31' controls the admission and exhaust of air from the cylinder 30 upon movement of piston 31 and is arranged to permit a rapid exhaust of air upon the release of the braking members by the electromagnet 28 while restricting the flow of air into cylinder 30. Due to the fact that the retarding force of this type of dash pot rapidly develops upon the initial movement of the piston 31, to draw air into the cylinder 30, the device operates with a substantially constant retarding force throughout the entire stroke of piston 31 and thus is capable of maintaining the braking members 25 and 26 disengaged for the time interval required for a car to pass over breaks of substantial length in the conductors adjacent the tracks. 85

90 Referring again to Fig. 1, the main track 15 is normally energized from an alternating current source of substantially constant frequency, not shown but which may be an ordinary commercial 60 cycle source, and the driving motors 16 and 17 are designed to operate the cars C and C', at relatively 95 high speed thereupon. 100

105 In order to permit slower movement of the cars in the loading zones of the several loading tracks 10, 11, 12, 13, and 14, the power conductors adjacent to these zones are arranged to be energized from a supply line 32 having a much lower frequency than that of the main track. The supply line 32, may, for example, be energized from a 10 cycle source as indicated in the 110 drawing and the several disconnecting switches 33, 34, 35, 36 and 37 may be provided for separately deenergizing the corresponding loading zones of tracks 10, 11, 12, 13 and 14 during inspection and repair 115 thereof. 120

125 It will be observed that the waiting zone of feeding track 14 is shown as sectionalized with short lengths of the power conductor for the cars located on opposite sides of the track in such space relation that the cars, C and C', may be supplied with power from the successive sections alternately through the current collecting shoes 18 and 19 with 130 which each motor driven car is equipped.

Suitable switch mechanism such as the drum controller 38 illustrated, is provided for successively connecting the sections of the waiting zone to a source of low frequency which may be the supply line 32 as shown in the drawing.

While not shown in detail in the drawing, it will be understood that the corresponding waiting zones of loading tracks

10, 11, 12 and 13 also are provided with sectionalized power conductors arranged to be successively energized in a similar manner to those illustrated and described in connection with the loading track 14.

15 In order to separately energize the dispatching zones of the loading tracks 10, 11, 12, 13 and 14 from a source of variable frequency, a motor generating set 39 comprising a direct current motor 40 and an alternating current generator 41 is provided and suitable switch mechanism such as the selective switch 42 is arranged to separately connect the generator 41 to any one of the several dispatching zones. The direct

20 current motor 40, as shown is of the shunt type and is supplied with power from a suitable source not shown in the drawing. The speed of motor 40 is varied to correspondingly vary the frequency of the alternating current generator 41 by means of the field regulating resistor 43 and the switch 44 controlling the same and the excitation of generator 41 is varied by means of a similar field regulating resistor 45 and controlling switch 46.

25 With the railroad cars C and C' and the loading portion of the railway system embodying my invention, constructed and arranged as previously described, the operation of the system is as follows:

30 When the disconnecting switches 33, 34, 35, 36 and 37 are closed the loading zones of the respective loading tracks 10, 11, 12, 13 and 14 are energized from a source of 35 relatively low frequency and the movement of the cars along the loading platform may be controlled readily by an operator standing or walking beside the car. After the cars are loaded, the drum controller 20 with

40 which the car is provided is moved to the position required to connect the motor for operation of the car from the loading zone to the waiting zone and the car proceeds on its way unattended.

45 In this way, a car such as the car C' will reach the normally deenergized waiting zone of loading track 14, and the driving motors of the car will be deenergized and the car stopped after a pre-determined time interval by the electromagnetic friction brakes with which it is equipped. The car C' may now be moved into coupling engagement with the car C by operating the drum controller 38 to successively energize the sections of the waiting zone of loading track

50 14. Upon the energization of the first section, the electromagnetic brake is released and the driving motors are energized to move the car C' towards a preceding car C at a relatively slow speed. With the cars 70 equipped with an automatic coupling arrangement as shown in Fig. 5, it will be obvious that by proper operation of the drum controller 38, the car C' may be moved into coupling engagement with the car C 75 without releasing the brakes or energizing the driving motors of the latter car and that the next car entering upon the waiting zone of loading track 14 may be coupled to the car C' in a similar manner. 80

When a suitable number of cars have been coupled into a train, the entire train may be moved from the waiting zone into the dispatching zone by operating the drum controller 38 to its extreme position.

85 It will be understood that the cars may be made up into trains in the waiting zones of loading tracks 10, 11, 12 and 13 in a similar manner to that previously described and moved therefrom to the dispatching zone of 90 the corresponding track. The trains of cars are then separately fed from the dispatching zone to the main track in the following manner. The motor generator set 39 is brought to its lowest operating speed by operating the switch 44 to the position shown in the drawing. Selective switch 42 is then operated to connect the alternating current generator 41 to the desired waiting zone which may be assumed to be the waiting 95 zone of loading track 14. This releases the electromagnetic brake of each car in the train and energizes the driving motors thereof at relatively low frequency. As the train starts, the switch 44 is operated to insert 100 successive portions of the regulating resistor 43 in the field circuit of direct current motor 40 and thereby increase the speed of motor generator set 39 and the frequency of alternating current generator 41.

105 At the same time, the switch 45 is operated to increase the voltage of alternating current generator 41 in order to increase the torque of the alternating current motors driving the train of cars. In this manner 110 the train of cars in the dispatching zone of loading track 14 is smoothly and efficiently accelerated. By proper operation of the switches 44 and 45 the train of cars may be rapidly accelerated in a short distance of 115 travel so that the train passes from the dispatching zone to the main track with the normal speed at which they operate thereupon. If desired, the interconnection of the power conductors of the dispatching zone of branch track 14 and the power conductors of the high speed main track 15 through the outgoing train of cars may be prevented by automatic switching apparatus of the type 120 which is fully described and broadly claimed 125

in the previously mentioned Jackson patent application. It will be obvious that the trains of cars in the dispatching zones of the other loading tracks are accelerated and fed to the main track by proper operation of the selective switch 42 and the controlling switches 44 and 46 in the manner previously described.

Referring now to the receiving portion of the automatic railway system illustrated in Fig. 4, it will be seen that the main track 15 joins with a plurality of receiving tracks 50, 51, 52, 53, 54, and 55 each of which may be provided with an electromagnetically actuated track switch of the type shown in connection with the receiving tracks 50 and 55. This form of electromagnetic track switch is operated to the closed position in which it is shown by an electromagnet 56 and is operated to the open position by a second electromagnet 57, each of which are under the control of a selector switch 58. The several electromagnetic track switches may be interlocked in the usual manner to insure the proper sequence of operation thereof and a track interlock switch 59 may be provided for preventing operation of the track switch while the train of cars is passing thereover if desired. However, the particular form of track switch and the interlocking arrangement therefor form no part of my present invention and hence need not be further described herein.

It will be observed that each of the receiving tracks 51, 52, 53, 54 and 55 has a normally deenergized decelerating zone adjacent to the junction with the main track and also is provided with an uncoupling zone which may be located adjacent to the decelerating zones as shown in the drawing or in other suitable portions of the receiving track. The decelerating zones of each of the receiving tracks are arranged to be energized from a source of variable frequency such as the motor generator set 60 which may be similar in all respects to the motor generator set previously described in connection with the loading portion of the automatic railway system. Likewise the selective switch 61, the speed controlling switch 62 and the voltage controlling switch 63 for the motor generator set may be similar to those previously described.

The uncoupling zone of each of the feeding tracks comprises two adjoining track sections as illustrated in the drawing, the first of which normally is energized at a lower frequency than the remainder of the normally energized receiving track and the second of which is energized at a higher frequency than the remainder of the receiving tracks.

In the uncoupling zone of each of the receiving tracks and adjacent to the track section energized at the lowest frequency is an

uncoupling cam 66 which is arranged to mechanically cooperate with the automatic couplers of the cars as shown more in detail in Fig. 5. The cam 66 is located between the tracks in the uncoupling zone and is so formed as to engage with and lift a roller 77 which is carried by a reciprocating plunger 78 on the forward end of each of the cars. As the plunger 78 is raised, the spring 79 is compressed thereby exerting a lifting force 75 on the coupler arm 80 through the uncoupling pin 81.

The operation of the receiving portion of the automatic railway system embodying my invention may be better understood by assuming that a train of cars after passing over the main line track 15 at high speed is switched therefrom to the receiving track 55 by operating the electromagnetic switch therefor in an obvious manner. As soon as the train of cars is upon the decelerating zone of receiving track 55, the selective switch 61 is operated to connect the generator of the motor generator set 60 to the decelerating zone and the speed controlling switch 62 and the voltage controlling switch 63 are operated simultaneously to decrease both the frequency and voltage applied to the driving motors of the cars composing the train. With the train running at high speed, the decrease in frequency and voltage produces an electrical braking effect in the driving motors which quickly reduces the speed thereof in an efficient and reliable manner and without applying the electromagnetic friction brakes.

With the speed of the train reduced to a suitable value, the cars enter upon the uncoupling zone. When the foremost car runs upon the section energized at the lower frequency the speed thereof is reduced and the couplings between this car and the next succeeding car is slackened. At the same time the uncoupling roller of the second car engages with the track cam 66 as illustrated in Fig. 5, and due to the slack in the coupling, the coupling arm is readily released. As the cars are uncoupled, the driving motors of the foremost car are energized on the succeeding track section at a higher frequency and consequentially this car is accelerated and moved away from the succeeding car. It will be understood that as each pair of succeeding cars enter upon the uncoupling zone, the automatic uncoupling thereof is effected in a similar manner to that just described and the individual cars then pass along the receiving track at relatively slow speed until they reach the proper unloading platform where they are stopped by an operator standing along side the track.

In accordance with the provisions of the patent statutes I have described the principle of operation of my invention together with the apparatus which I now consider to rep-

resent the best embodiment thereof, but I would have it understood that the apparatus shown is only illustrative and that the invention may be carried out by other means.

5. What I claim as new and desire to secure by Letters Patent of the United States is:

1. The combination of a normally energized alternating current electric railway system having a plurality of branch tracks 10 joining a main track and a plurality of alternating current motor driven cars arranged to operate automatically thereon, each of said branch tracks having a normally deenergized section adjacent said main track
- 15 for automatically stopping the cars thereupon, an alternating current source of variable frequency, switch mechanism for separately connecting said source to each of said sections to operate the cars thereon, and
- 20 means for controlling the frequency of said source to gradually accelerate said cars.

2. The combination of a normally energized alternating current electric railway system having a plurality of feeder tracks 25 joining a main track and a plurality of alternating current motor driven cars arranged to operate automatically thereon, each of said feeder tracks having a normally de-energized section for automatically
- 30 stopping the cars passing thereupon, an alternating current source of variable voltage and frequency, switch mechanism for separately connecting said source to each of said sections and for increasing the frequency and voltage of said source to accelerate and feed the cars stopped thereupon to said main track.
- 35 3. The combination of a normally energized alternating current electric railway

- 40 system having a main track joining a plurality of receiving track and a plurality of alternating current motor driven cars arranged to operate thereon, each of said receiving tracks having a normally de-energized section adjacent said main track, of an alternating current source of variable frequency, switch mechanism for separately connecting said source to each of said sections, and means for decreasing the frequency of said source to electrically decelerate the cars passing from said main track to said sections.
- 45 4. The combination of a normally energized alternating current electric railway

- 50 system having a plurality of branch tracks joining a main track and a plurality of alternating current motor driven cars arranged to operate automatically thereon, each of said branch tracks being energized
- 55 at a lower frequency than said main track and having a normally de-energized section adjacent thereto, a variable speed motor gen-

erator set comprising a direct current motor and an alternating current generator, switch mechanism for selectively connecting said generator to each of said sections and for controlling the speed of said motor to vary the frequency of said generator and thereby correspondingly varying the operating speed of the cars passing upon said sections.

5. An automatic alternating current electric railway system comprising a plurality of feeder tracks joining a normally energized main track and a plurality of alternating current motor driven cars arranged to operate thereon, each of said feeder tracks having a normally de-energized dispatching zone adjacent said main track and a sectionalized waiting zone disposed adjacent thereto, and means comprising switch mechanism for establishing separate power connections for the successive zones of each of said feeder tracks to feed the cars thereupon to said main tracks.

6. An automatic alternating current electric railway system comprising a plurality of feeder tracks joining a normally energized main track and a plurality of alternating current motor driven cars arranged to operate thereon, each of said feeder tracks having a normally de-energized dispatching zone adjacent said main tracks and a sectionalized waiting zone disposed adjacent thereto, of switch mechanism for successively energizing the sections of said sectionalized waiting zone to move the cars therefrom to the corresponding dispatching zone, and means including a source of variable voltage and frequency for separately energizing said dispatching zones to move the cars therefrom to said main track.

7. An automatic alternating current electric railway system comprising a plurality of feeder tracks joining a normally energized main track and a plurality of alternating current motor driven cars arranged to operate thereon, each of said cars having a coupler at each end thereof and each of said feeder tracks having a normally de-energized dispatching zone adjacent said main track and a sectionalized waiting zone disposed adjacent thereto, switch mechanism for successively energizing the sections of said sectionalized zone to individually move the last car entering thereupon into coupling engagement with the preceding car, and means including a source of variable voltage and frequency for accelerating and feeding a coupled train of cars from each of said dispatching zones to said main track.

In witness whereof, I have hereunto set my hand this 19th day of November, 1924.

-- ROBERT H. McLAIN.
